CARL E. JOHNSON, OF LOS ANGELES, CALIFORNIA, ASSIGNOR TO UNITED STATES ELECTRICAL MANUFACTURING COMPANY, OF LOS ANGELES, CALIFORNIA, A CORPORATION OF CALIFORNIA.

BRAKE ATTACHMENT FOR SEWING-MACHINES.

1,027,339.

Specification of Letters Patent.

Patented May 21, 1912.

Application filed February 3, 1910. Serial No. 541,892.

To all whom it may concern:

Be it known that I, CARL E. JOHNSON, a citizen of the United States, residing at Los Angeles, in the county of Los Angeles, 5 and State of California, have invented a new and useful Brake Attachment for Sewing-Machines, of which the following is a specification.

This invention relates to a brake which may 10 be attached to a sewing machine, and one of the main objects of the invention is to provide a brake for sewing machines which is in the form of an attachment which can be applied to any of the ordinary types of sewing machines by any person without requiring any alteration of the machine or any tools other than an ordinary screw driver.

The attachment is particularly designed 20 to be used with sewing machines which are operated by a motor, and a further object is to provide for automatically applying the brake when the power is reduced or thrown off entirely from the sewing machine.

The device is of particular advantage 25 when employed as an attachment in connection with the motor attachment for sewing machines and the like which forms the subject of a former patent of mine issued September 7th, 1909, No. 933,710, in which 30 the motor is mounted upon the treadle of the sewing machine and connected by belt with the driving wheel of the sewing machine in such a manner that the belt may be tightened or loosened by manipulating the 35 treadle, power being applied to the machine when the belt is tightened and power being thrown off from the sewing machine when the belt is slackened, and a further object of the present invention is to cause the brake

40 to be automatically applied to stop the sewing machine when the belt is slackened, so that the operator of the sewing machine is not required to devote any attention to the application or release of the brake and 45 is thus left free to give his attention to the regular work. Thus, by a natural movement of the treadle the brake is released and the belt is tightened and the machine is started into operation and run by the motor until 50 such time as the operator wishes to stop the machine, whereupon a simple movement of the foot of the operator tilts the treadle in the opposite direction which loosens the belt, throwing off the power to the machine and

55 at the same time automatically applying the brake to the machine, so that the machine is stopped automatically and instantly upon throwing off the power.

The device is so constructed that it may be attached to machines having a drop head 60 as well as those having a stationary head, without requiring any alteration in either the machine, or the brake attachment.

Other objects and advantages of the invention will be brought out in the following description.

Referring to the drawings:—Figure 1 is an end elevation of a sewing machine, a portion of which is broken away to show the connection of the attachment. Fig. 2 is a 70 side elevation of the attachment on an enlarged scale. Fig. 3 is a plan view of the attachment.

The attachment comprises a clamp consisting of two clamping members 1 and 2 75 having hooks 3 at each end which are adapted to be inserted in the holes in the sewing machine table 4 through which the belt 5 passes, and to be clamped against the intervening portion of the table which lies between the two belt holes. The clamp members 1 and 2 are preferably formed of sheet metal, the member 1 having an upwardly extending loop 6 for the attachment of the lower end of a coil spring 7 and having an up-turned lug 8 through which a tightening screw 9 extends, the latter being screwed into a similar lug 10 formed on the clamping member 2.

Extending up at one side of the clamping member 2 is a bracket 11 to which a brake lever 12 is pivoted by means of a screw 13. One end of the brake lever 12 is provided with a laterally projecting lug 14 to which a hook 15 is adjustably connected by nuts 16, 95 the hook 15 being connected to the upper end of spring 7. By adjusting nuts 16 the tension of the spring 7 may be regulated. The other end of the brake lever 12 is provided with an off set brake shoe 17 which 100 has a leather lining 18, the brake shoe being curved to present a concave face against the rounded rim of the fly wheel 19 of the sewing machine. A wire or other connection 20 extends from a perforation 21 in the lever 12 to the treadle 22 of the sewing machine.

23 designates the motor mounted on the treadle 22, and 24 is the belt from the motor

to the driving wheel 25 of the sewing machine.

26 is a spring counteracting the weight of the motor 23, the tension of which is preferably sufficient to normally carry the weight of the motor 23 so that the belt 24 is slack.

The treadle 22 is pivoted to the sewing machine at 26 and the wire 20 is connected 10 to the treadle at 27 at a point a sufficient distance from the fulcrum 26 to produce the requisite movement of the brake lever 12 when the treadle 22 is operated.

The brake attachment is readily applied 15 to the sewing machine by simply slipping the hooks 3 into the holes of the table and then screwing up the screw 9 to clamp the hooks 3 tightly, as shown in Fig. 1. The wire 20 may then be easily connected to the 20 treadle by passing it down through one of the holes near the belt 5.

In the normal position of the parts the motor 23 is sustained by spring 26 with the 25 belt 24 slackened, so that as the motor 23 operates no power is transmitted to the sewing machine. As the motor 23 is thus sustained by the spring 26 the wire 20 is relaxed and the spring 7 holds the brake lever 12 tilted so that the shoe 17 bears against the fly 30 wheel 19 and prevents the machine from running, although the machine may easily be turned in either direction to try the needle or for any other purpose by pressing upon the treadle slightly enough to release the 35 brake without making the belt 24 taut. When it is desired to operate the sewing machine by the motor, the treadle 22 is operated to stretch the spring 26 and lower the motor 23, thereby making the belt 24 taut, 40 wherupon power is transmitted to the driving wheel 25 of the sewing machine, and the latter is started into operation. As the treadle 22 is thus operated the wire 20 is pulled down which tilts the brake lever 12 45 and throws the shoe 17 out of contact with the fly wheel 19, thus automatically releasing the brake upon the application of the power. When the power is thrown off by relaxing the pressure on the treadle, the 50 spring 26 raises the motor and relaxes the belt 24 and at the same time the wire 20 is relaxed permitting the spring 7 to act upon the lever 12 and swing the brake shoe 17 into contact with fly wheel 19, thus instantly 55 stopping the sewing machine automatically upon throwing off the power.

What I claim is:—

1. A brake attachment for sewing machines, comprising a pair of clamping mem-

bers with hooks adapted to engage in the 60 belt holes in the table of the sewing machine, a brake lever pivoted to one of said clamping members, a brake shoe on the brake lever adapted to bear against the fly wheel of the machine, and a spring between 65 the brake lever and the other clamping member for normally holding the brake shoe against said fly wheel.

2. A brake attachment for sewing machines, comprising a pair of clamping members, each having a hook adapted to engage 70 in a belt hole in the table of the machine, means for drawing said clamping members toward each other, a bracket on one of said members, a brake lever pivoted to said 75 bracket, a brake shoe on said lever adapted to bear against the fly wheel of the machine, a loop formed on the other clamping member, a coil spring connected to said loop, and a hook adjustably secured to the brake lever 80 and connected to the other end of said coil spring.

3. A brake attachment for sewing machines comprising a pair of clamping members, each having a hook adapted to engage 85 in a belt hole in the table of the machine, means for drawing said clamping members toward each other, a bracket on one of said members, a brake lever pivoted to said 90 bracket, a brake shoe on said lever adapted to bear against the fly wheel of the machine, a loop formed on the other clamping member, a coil spring connected to said loop, a hook adjustably secured to the brake lever 95 and connected to the other end of said coil spring, and a connection extending from the brake lever to the treadle of the sewing machine for operating the brake lever when the treadle is operated.

4. A brake attachment for sewing machines, comprising a pair of clamping members, each having a hook adapted to engage 100 in a belt hole in the table of the machine, means for drawing said clamping members toward each other, a bracket on one of said 105 members, a brake lever pivoted to said bracket, a brake shoe on said lever adapted to bear against the fly wheel of the machine, and a coil spring having one end attached to the brake lever and the other end attached to the other clamp member.

In testimony whereof, I have hereunto set my hand at Los Angeles, California, this 24th day of January, 1910.

CARL E. JOHNSON.
